Specification for Design.

Patented Mar. 2, 1920.

Application filed August 23, 1917. Serial No. 187,892. Term of patent 7 years.

To all whom it may concern:

Be it known that I, MATHIAS WEIWODA, a citizen of the United States, residing in the city of New York, borough of Brooklyn, in the county of Kings and State of New York, have invented a new, original, and ornamental Design for a Casing for Indicators, such as Clocks, Barometers, or the like, of which the following is a specification, reference being had to the accompanying drawings, forming part thereof.

Figure 1 is a plan view of an indicator casing; and

Fig. 2 is a side elevation of the same, showing my new design.

I claim:

The ornamental design for a casing for indicators, such as clocks, barometers, or the like, as shown.

MATHIAS WEIWODA.
